UNITED STATES PATENT OFFICE.

KAZIMIERZ KLIMEK, OF GOWANDA, NEW YORK, ASSIGNOR OF ONE-HALF TO STAMSLAW FLIS, OF GOWANDA, NEW YORK.

DESIGN FOR A PICTURE FRAME.

Application filed May 19, 1924. Serial No. 9,648. Term of patent 3½ years.

To all whom it may concern:

Be it known that I, KAZIMIERZ KLIMEK, citizen of Poland, residing at Gowanda, in the county of Cattaraugus and State of New York, have invented a new, original, and ornamental Design for Picture Frames, of which the following is a specification, reference being had to the accompanying drawing, forming a part thereof.

The figure is a plan view of a picture frame showing my new design.

The design illustrated extends completely around the frame.

I claim:

The ornamental design for a picture frame, as shown.

KAZIMIERZ KLIMEK.
